[57] CLAIM

The ornamental design for a rear and side wall structure for a motor vehicle, as shown and described.

DESCRIPTION

FIG. 1 is a perspective view of a rear and side wall structure for a motor vehicle;

FIG. 2 is a front view of the rear and side wall structure for a motor vehicle;

FIG. 3 is a top view of the rear and side wall structure for a motor vehicle;

FIG. 4 is a left side view of the rear and side wall structure for a motor vehicle; and,

FIG. 5 is a right side view of the rear and side wall structure for a motor vehicle.

The broken lines shown in FIG. 1 are for illustrative purposes only and form no part of the claimed design.
